RADIO CIRCUIT

Filed Oct. 30, 1930

UNITED STATES PATENT OFFICE

AUGUST F. P. STENZY, OF BALTIMORE, MARYLAND, ASSIGNOR OF ONE-HALF TO
STEPHEN RATAJCZAK, OF BALTIMORE, MARYLAND

RADIO CIRCUIT

Application filed October 30, 1930. Serial No. 492,341.

This invention relates to a radio receiving circuit and it aims to generally improve existing types and especially to provide means causing the sound waves which are 5 attracted to follow a direct course, to amplify such sound waves to the maximum without distortion and before passage into the detector tube, for audio amplifying and passage to the loud speaker without distortion so that the most natural rendition will 10 be realized.

It is also aimed to provide a circuit which is extremely sensitive and will attract the 15 slightest or very feeble high frequency sound waves and reproduce the same in volume from great distance.

The more specific objects and advantages 20 will become apparent from a consideration of the description following taken in connection with accompanying drawing in which the view illustrates the invention in 25 electrical diagram.

Referring specifically to the drawing 10 designates the input wire connected through 25 a condenser at 11 with an antenna 12 and leading through a condenser 13 to ground at 14. Such wire connects with the radio, the circuit having suitable connection with a source of electrical energy.

30 One or more radio frequency tubes are employed as at 15 while a detector tube is used at 16, an audio frequency tube at 17 and a rectifier tube at 18.

A power transformer is shown at 19 and 35 from one coil 20 thereof a wire or conductor 21 extends, the same having branches 22 leading to the grid of the tubes 15 and each including a secondary coil 23 and a condenser 24. One of the secondary coils 23 is part 40 of the receiving coil which is completed by the primary 25, connected in the line 10.

The other secondary 23 coacts with a primary 26, forming a transformer, and arranged in a conductor 27 including the plates 45 of the radio frequency tubes 15 and also including a primary winding 28 of another transformer. Such conductor 27 further includes a secondary coil 29, the terminal of such wire 27 leading to the positive side of 50 a filter condenser 30 and also being connected

at 31 to a resistance strip 32. The wire 21 is also connected to the resistance strip at 33 and at 34 is connected to the negative side of the filter condenser 30.

A conductor 35 leading from conductor 21 55 extends to the grid 36 of the detector tube 16 and includes a secondary at 37 associated with the primary 28 and secondary 29 and also includes a fixed condenser 38, and a variable resistance 39, of the type which has 60 no winding. The grid 36 has a push-pull input transformer 40 or a suitable audio transformer of a ratio of six to one, more or less. These connections cause tuned inductance super regeneration of the incoming 65 high frequency and picks up the regenerated radio frequency passed on from the radio frequency tube plates regenerated by coil 29 and passes the amplified sound waves to the detector tube grid 36.

A conductor 41 leads from the plate of the detector tube 16 and has therein the primary 42 of a transformer completed by a secondary 43, such conductor 41 being connected at 44 to the resistance strip 32 and terminating at the positive side of the filter condenser 30. A conductor 46, including the secondary 43 70

leads to the grid 47 of the audio amplifying tube 17. From the plate 48 of the latter, a conductor 49 leads which may include the 75 loud speaker 50, such conductor being connected at 51 to the resistance strip 32 and terminating at the positive side of the filter condenser 30. A continuous conductor 52

includes the filament 53 of each of the tubes 80 15, 16, 17 and 18 and also a coil 53 of the power transformer 19. From the conductor 52, a conductor 54 leads, having choke coils 85 55 therein to protect the loud speaker 50, and also having therein a variable high resistance 56 associated with a conductor 57 connected at 58 to the resistance strip 32 and at its other end terminating at the positive side of the filter condenser 30. Also a wire 90 59 extends from the conductor 54 to such positive side of condenser 30 and from the same side of said condenser 30, a wire or conductor 60 extends to a contact 61 adjacent the resistance strip 32. Conductors 62 also 95 extend from the wire 21 to the filaments 53 of 100

the conductor tubes 15 and detector tube 16.

From the plate 62 of the rectifier tube 18, a conductor 63 extends to the coil 20 and from the latter a conductor 64 extends to the 5 grid 65 of said rectifier tube 18.

Various changes may be resorted to provided they fall within the spirit and scope of the invention.

I claim as my invention:—

- 10 1. In a radio receiving circuit, a plurality of indirectly heated cathode tubes, a rectifier tube having a filamentary cathode, means for energizing the cathodes of all of said tubes comprising a series circuit including the heater elements of said indirectly heated cathode tubes, the cathode of said rectifier tube and a source of alternating current, means for energizing the anode circuits of the indirectly heated cathode tubes from a 20 source of alternating current which is rectified by said rectifier tube.
- 25 2. In a radio receiving circuit, a plurality of indirectly heated cathode tubes consisting of a radio frequency tube and a detector tube, a rectifier tube having a filamentary cathode, means for energizing the cathodes of all of said tubes comprising a series circuit including the heater elements of said indirectly heated cathode tubes, the 30 cathode of said rectifier tube and a source of alternating current, means for energizing the anode circuits of the indirectly heated cathode tubes from a source of alternating current which is rectified by said rectifier tube.
- 35 3. In a radio receiving circuit, a plurality of indirectly heated cathode tubes consisting of a radio frequency tube, a detector tube, and an audio frequency tube, a rectifier tube having a filamentary cathode, means for energizing the cathodes of all of said tubes comprising a series circuit including the heater elements of said indirectly heated cathode tubes, the cathode of said rectifier tube and a source of alternating current, means for energizing the anode circuits of the indirectly heated cathode tubes from a 45 source of alternating current which is rectified by said rectifier tube.
- 50 50. In testimony whereof I affix my signature.

AUGUST F. P. STENZY.
